UNITED STATES PATENT OFFICE.

ERNEST H. WEBB, OF NEW BRUNSWICK, NEW JERSEY, ASSIGNOR TO CHASE COMPANIES, INC., OF WATERBURY, CONNECTICUT, A CORPORATION OF CONNECTICUT.

APPARATUS FOR CARDING SAFETY PINS.

Application filed March 19, 1924. Serial No. 700,209.

This application is a partial continuation of my copending case, Serial No. 551,972, filed April 12, 1922, and contains subject matter taken therefrom.

This invention relates especially to apparatus for carding safety pins and similar articles by forming the cards with transverse or other slots or apertures into which the closed or locked safety pins may be inserted, particularly if the card is transversely arched up when the pins are inserted in the slots. Then a breakable cardboard or other retainer strip may be slipped along the back of the card and may preferably have bottom or edge projections so as to interlock with the inserted pins and securely and positively retain them in position until they are removed for use and thereupon tear or break the retainer strip which is preferably adhesively secured to the card back at a number of places or positively retained in position as by interlocking projections, tongues and apertures formed in the cooperating portions of the strip and card or pins. The card may be conveniently supported and forced into its transversely arched up position in a card holder having inclined card grooves on each side, so that when the card is forced longitudinally into the grooves or when the grooved edge portions approach each other the card is arched up transversely along its centre line or where the transverse pin slots are formed therein. A dozen or other desired number of closed safety pins may be placed or fed into a suitable pin transfer block having slots to receive them and may be hereby transferred and accurately placed in cooperation with the pin card so that for instance their point portions enter and pass through the card slots sufficiently to allow the retainer strip to be inserted from the same or the opposite direction as the card. Then the pins may be ejected from the transfer block by any suitable device and the card released from the holder and discharged therefrom as by the insertion of another unfilled card into the holder.

In the accompanying drawing showing in a somewhat diagrammatic way an illustrative embodiment of this invention:

Fig. 1 is a central longitudinal section through an illustrative carding apparatus;

Fig. 2 is a transverse section showing the strip feeding and gumming devices;

Fig. 3 is a transverse section thereof taken substantially along the line 3—3 of Fig. 1;

Fig. 4 is a rear view of the resulting pin card or package, and Fig. 5 is a section thereof on line 5—5 of Fig. 4.

The pins may be carded or packaged according to this invention while remaining in their closed or locked condition in which they are regularly tumbled and polished and for this purpose the pin card 14 is formed with one or more series of pin slots such as 16 which may be transversely arranged when a single row of pins is to be arranged on the card. The pins preferably have their point members inserted through these slots which can be readily done by hand or otherwise, especially if the pin card is transversely arched up by any suitable means; and when all of these safety pins, rings or other generally similar articles have been inserted into their slots, a cardboard or other retainer strip or member 15 is inserted between the card back and the projecting portions of the articles extending through the slots so as to hold them in position during shipment for instance, the retainer strip being preferably adhesively secured to the card back either throughout their cooperating faces or at several points along the same.

An illustrative device for use in forming such a package is shown in Figs. 1 and 3 as comprising a card holder 2 which is preferably formed with a movable side or section 6 mounted to slide laterally on the guide pins 8, each of which may have a threaded end 9 extending into the main card holder 2. A spring such as 29 may be arranged around the reduced end 7 of the pin so as to tend to separate the card holder sections when the bushing 33 is screwed in behind the spring. These sections may, however, be closed by suitable devices such as one or more cams 10 pivoted about the pivots 11 in the ends of the pins 7 so that when the ends 12 of these cams are swung upward into the position indicated in Fig. 3 the card holder sections are closed against the action of these springs 29 and the card 14 is thereby forced up into the definitely transversely arched up position indicated. The card holder is preferably formed with inclined

2
card grooves 3 on either side of the same so that under these conditions the card edges are forced down along these inclined grooves to the curved bottom portions 4 thereof, the 5 arched up lower surface of the card holder recess promoting the desired position of the card adjacent these groove edges.

The safety pins or other generally similar articles may be inserted, in any suitable way 10 in these pin slots in the card which are preferably not more than about half as long as the safety pins in order to more definitely hold them in position. For this purpose a pin transfer block such as 18 is desirable 15 in supporting the series of pins and facilitating their insertion in the slots in the card. This transfer block may be formed with a series of pin slots 19 which may extend completely through the block from top to bottom, if desired, and be spaced apart so as to correspond with the slots in the card 14. To retain the pins in position in the transfer block any suitable holding devices such as one or more pin supporting plates 20 20 may be employed and mounted, if desired, on the pins 31 projecting from each side of the transfer block 18 and normally forced inward into the position indicated in Fig. 3 by the light springs 21 so that the series of safety pins are thus supported by the inwardly projecting edges of these plates. These plates may, however, be released so as to simultaneously release the series of safety pins from the transfer block and for this 30 purpose the plate releasing cams 22 may be arranged on or adjacent the upper face of the transfer block so as to be engaged by the edges 24 of the pin releasing block 23 during the downward movement toward the transfer block, so that it then wedges outward these releasing cams and the connected pin supporting plates 20. If desired also 40 resilient or rigid ejector members may be provided on this releasing block and one or more pin ejector lugs 27 may be formed or yieldably mounted thereon so as to engage the safety pins preferably after the supporting plates have been substantially released and thereupon positively eject the safety pins from the transfer block by passing into the slots 28 in the block. The releasing block may be supported and operated in any desired way as by the tubular carrier members 26 which may extend 50 around the carrier rods 25 secured to the diagonally opposite corners or portions of the transfer block, for example, these carrier elements being operated manually or mechanically in any desired way.

60 In using this apparatus to form the pin package described the pin card 14 may be inserted into the laterally opened grooved card holder as by the feed roller 50 which engages the lower face of the card beneath

the guide 45, while the feed-arms 51 are in their retired position and out of the path of the card, which has sufficient momentum to carry it forward after passing out of engagement with the feed-roll 50. The oscillating feeding arms 51 are finally swung up by the shaft 52 to force the card forward between the guide 46, 47, 47' until it engages the card aligner 30 pivoted about the pin 37 in the holder so that it may be swung into this aligning position or swung downward to allow the filled card to be longitudinally discharged from the holder, if desired. When the card is longitudinally positioned in the holder the holder sections may be brought together as by the closing cams 10 so as to transversely arch up the card which may thus be forced up at its central portion somewhat above its transverse guide ribs 3 formed in the upper surface of the card holder and the pin recesses 13 therein as shown in Figs. 1 and 3. Then a series of safety pins may be brought into proper engagement with the card as by the pin transfer block 18 so that the point or other portion of each pin is preferably pushed through the corresponding pin slot in the card to a sufficient extent to leave an opening into which the retainer strip 15, having bottom or edge corrugations such as 35 to accommodate the pins and preferably having gummed or otherwise adhesive upper surface or portions 36, 37 may be inserted as by the strip feeder 1. As the retainer strip is fed forward over the guide 45 by the feeder 1 or other means, the gumming roll 40 is simultaneously rotated so as to apply any suitable adhesive from the tank 44 and supply roll 43 to the desired part of the retainer strip. As shown in Fig. 4, the strip may have rounded edge corrugations or locking projections extending between adjacent pins to be thereby secured in position, and these edge projections may be advantageously gummed as by contact with the lateral projecting flanges or conical portions 42 of the gumming roll 40, see Fig. 2. These gummed edge projections are of course strongly forced into engagement with the card back as soon as the card is released from the holder so that it can spring back into flatter position which forces the pins and interposed retainer strip upward. Other separated or continuous gummed portions may be provided instead of or in addition to these gummed edge projections, and for this purpose the gumming roll 40 may have projections 41 at the proper intervals to apply the separated spots 37 of gum to the back of the strip 15, preferably between each two adjacent pins. The retainer strip is guided as by suitable guides 45, 48 so as to pass beneath the arched up card 16 and above the pins projecting through the card

as is seen in Fig. 1, the one or more feeders 1 passing through suitable slots such as 49 in the gumming roll 40.

- Thereupon the pins may be released from 5 the transfer block as by the further descent of the releasing block 23 which releases and ejects the pins from the transfer block and also, if desired, forces portions of the gummed or adhesive surface of the retainer 10 strip into holding engagement with the card back as by the downwardly projecting end or other portions such as 34, 35 of the releasing block which may force these card board elements tightly together. The transfer 15 and releasing block may then be withdrawn and the card of pins withdrawn from the card holder preferably after the holder sections have been opened at least to some extent to facilitate this withdrawal.
- 20 In some cases it is advantageous to employ interlocking projections or tongues and apertures formed in the cooperating portions of the retainer strip and card. This method may be employed alone or supplemental to 25 the adhesive method. As shown in Fig. 4, any desired number of apertures 38 may be formed in these parts as by severing them along the crossed or perpendicular dotted lines 37' by means of one or more sharp 30 edged piercing members, and then forcing back against the adjacent rear face of the retainer strip, for instance, the interlocking tongues or projections 39 which are thus formed. Where this is done by a stamping 35 or die operation under heavy pressure, the adhesive which has preferably been applied between these parts, tends to become quickly set as in box staying operations and materially helps to hold the parts together in such 40 positions as are shown in Figs. 4 and 5. If desired, however, a number of apertures such as 38' may be pierced in these cooperating members of heavy paper or light card-board so as to force the tongues 39' through 45 this aperture after which they may be advantageously forced or crushed down against the back of the retainer strip, for example, to prevent accidental longitudinal displacement of the retainer strip.
- 50 This invention has been described in connection with a number of embodiments, forms, proportions, parts, arrangements, materials, methods of connection, operation and use, to the details of which disclosure the invention is not of course to be limited, since 55 what is claimed as new and what is desired to be secured by Letters Patent is set forth in the appended claims.

I claim:—

- 60 1. The apparatus for carding safety pins or similar articles, comprising a multiple section card holder formed with lateral card engaging members and formed with an upwardly arching intermediate portion provided with transverse recesses, means for

closing and opening the sections of said card holder to arch up a transversely slotted card, a cooperating transfer block having a series of transversely spaced slots corresponding to the transverse slots in said card, means to 70 releasably retain said articles on said transfer block and to disengage them therefrom when they have been inserted in the slots in said card, gumming devices comprising a gumming roll having circumferentially 75 separating gumming projections and conically projecting lateral gumming portions to apply adhesive to the separated edge projections of a paper retainer strip, and means to insert said retainer strip between the card 80 back and the inserted articles.

2. The apparatus for carding safety pins or similar articles, comprising a card holder formed with lateral card engaging members and formed with an upwardly arching intermediate portion provided with transverse recesses, means cooperating with said card holder to arch up a transversely slotted card, a cooperating transfer block having a series of transversely spaced slots corresponding to the transverse slots in said card, means to 85 releasably retain said articles on said transfer block and to disengage them therefrom when they have been inserted in the slots in said card, gumming devices comprising a gumming roll having conically projecting lateral 90 gumming portions to apply adhesive to the separated edge projections of a paper retainer strip, and means to insert said retainer strip between the card back and the inserted articles.

3. The apparatus for carding safety pins or similar articles, comprising a card holder, cooperating means to arch up a transversely slotted card, a cooperating transfer device 105 to insert a series of articles in the slots in said card, gumming devices comprising a gumming roll having projecting lateral gumming portions to apply adhesive to the separated edge projections of a paper retainer 110 strip, and means to longitudinally insert said retainer strip between the card back and the inserted articles.

4. The apparatus for carding safety pins or similar articles, comprising a card holder, cooperating means to arch up a transversely slotted card, a cooperating transfer device to insert a series of articles in the slots in said card, gumming devices to apply longitudinally separated portions of adhesive to 115 a paper retainer strip, and means to longitudinally insert said retainer strip between the card back and the inserted articles.

5. The apparatus for carding safety pins or similar articles, comprising a card holder 125 to hold and arch up a slotted card, means to insert a series of articles into said slots from the front of said card, gumming devices comprising a gumming roll having circumferentially separated gumming projections 130

4 and projecting lateral portions to apply separated portions of adhesive to a paper retainer member, and means to insert said retainer member between the card back and the inserted articles.

5 6. The apparatus for carding safety pins or similar articles, comprising a card holder to hold a slotted card, means to insert a

series of articles into said slots from the front of said card, gumming devices to apply separated portions of adhesive to a paper retainer member, and means to insert said retainer member between the card back and the inserted articles. 10
